UNITED STATES PATENT OFFICE.

GEORGE W. LILLY, OF CENTER, MISSOURI, ASSIGNOR OF ONE-FIFTH TO H. B. NORTON,
ONE-FIFTH TO H. L. SMITH, ONE-FIFTH TO J. S. CUPP, AND ONE-FIFTH TO A. W.
SAPP, OF CENTER, MISSOURI.

GRAVITY-HINGE.

1,206,869.

Specification of Letters Patent.

Patented Dec. 5, 1916.

Application filed September 21, 1916. Serial No. 121,467.

To all whom it may concern:

Be it known that I, GEORGE W. LILLY, a citizen of the United States, residing at Center, in the county of Ralls, State of Missouri, have invented a new and useful Gravity-Hinge, of which the following is a specification.

The object of my invention is to provide a hinge of novel construction adapted to close the door by gravity; to provide a hinge so constructed as to support the door so that it will not sag; and to provide a hinge that will permit of the door being taken down without the removal of any screws.

It is further my object to provide a hinge that will allow the door to stand open when pushed beyond ninety degrees from the closed position.

It is an especial object of my invention to eliminate the necessity for springs to close the door.

It is also an object of my invention to provide a hinge that can be regulated easily as to its closing qualities.

I attain the objects of my invention by the mechanism illustrated in the accompanying drawings, in which—

Figure 1 is a view of my invention applied to a door; and Fig. 2 is a detail horizontal sectional view of the hinge.

Like characters of reference designate like parts in each of the views.

Referring to the accompanying drawings, 2 designates the door and 1 the door frame. 35 A hinge rod 7 is secured to the door frame by suitable straps 3 and fastening members 4. I provide a bifurcated lever 9 having its outer end portion extending slidably through the screw-eye 14 which is fastened 40 to the approximate center of the door, as illustrated. The hooked end 10 of lever 9 is slidably engaged about hinge rod 7. The lower arm 11 of the bifurcated lever has a downwardly turned end 12 engaged in an

45 aperture 13 of the L-shaped plate 5 in its outturned portion 6 at a point substantially beyond the hinge rod 7 as illustrated in the drawings. It is within the contemplation of my invention to change the position of

aperture 13 and thereby to regulate the closing qualities of the door. The door is slidably supported relative to hinge rod 7 by suitable looped straps 8.

In operation as the door is opened the portion of the bifurcated lever 9 extending through screw-eye 14 gradually moves upward as it swings outward, the screw-eye, which supports the door, gradually moving along on lever 9 and thus elevating the door as it is opened up to approximately 90 degrees from its closed position. The looped straps 8 slide freely upward on hinge rod 7 and balance the door. When the door is released its weight bearing on the bifurcated lever 9 will cause the door to swing to its closed position, this operation resulting from the offset position of the end 12 of arm 11 of the lever 9 relative to the position of hooked end 10 of the other arm of the lever, which engaged about hinge rod 7. I may 70 change the position of aperture 13, and thus modify the inclination of lever 9, which will modify the operation of the gravity hinge accordingly. The door will stand open when pushed past the right angle arc, or substantially 75 beyond 90 degrees from closed position.

It is within the contemplation of my invention to apply my hinge to doors of all kinds, and especially to screen doors, barn doors and gates.

What I claim is:

In a gravity hinge, the combination of a door frame having a substantially vertical rod mounted thereto, a door having strap members slidably engaging the aforesaid rod, a bifurcated lever having a looped arm slidably engaging the rod and having a second arm engaging a member attached to the door frame at a point substantially beyond the rod, the aforesaid member affixed to the door frame, and a member affixed to the door through which the end of the bifurcated lever projects.

GEORGE W. LILLY.
